UNITED STATES PATENT OFFICE.

WILLIAM A. SCHOLLMAYER, OF YONKERS, NEW YORK.

SHINGLE.

Application filed November 4, 1926. Serial No. 146,244.

This invention relates to shingles and particularly to a device for securing and spacing shingles.

The invention has particular application to composition shingles such as asphalt or asbestos shingles. Shingles of this type have a tendency, because of their flexibility, to blow up from the roof, thus admitting air beneath the shingles. When the shingles are blown up rain and snow can enter beneath the shingle.

Furthermore, it is difficult in a roof of the type specified to prevent the wind from blowing between the spaces between adjacent shingles.

One of the objects of the invention is to provide means for securing the butts of the shingles in such a manner that they cannot be blown up or raised from the roof.

Another object of the invention is to provide means for facilitating the laying of the shingles.

Another object of the invention is to provide means whereby the shingles can be easily, accurately and uniformly spaced.

Another object of the invention is to provide means whereby the shingles can be laid and secured with the use of a minimum number of nails.

Further objects of the invention will appear from the following specification taken in connection with the drawings, which form a part of this application, and in which—

Fig. 1 is a perspective view of a shingle having a device secured thereto constructed in accordance with the invention;

Fig. 2 is a sectional elevation taken substantially on line 2—2 of Fig. 1;

Fig. 3 is a plan view showing portions of a plurality of shingles and the manner of using the devices carried by the shingles;

Fig. 4 is an enlarged sectional elevation taken substantially on line 4—4 of Fig. 3;

Fig. 5 is an enlarged sectional elevation taken substantially on line 5—5 of Fig. 3;

Fig. 6 is a perspective view similar to Fig. 1 but showing the device secured to a shingle of slightly different shape;

Fig. 7 is a sectional elevation taken substantially on line 7—7 of Fig. 6;

Fig. 8 is a plan view similar to Fig. 3 but showing a different manner of laying the shingles;

Fig. 9 is an enlarged sectional elevation

taken substantially on line 9—9 of Fig. 8; 55 and

Fig. 10 is an elevational view showing the manner of packing the shingles.

The invention briefly described consists of a shingle having a device preferably 60 formed of sheet metal, permanently secured along one of the edges thereof. This device is adapted to overlap an edge of an adjacent shingle and to be secured thereto by securing means such as a nail, which is driven 65 through the overlapping portion of the device and the overlapping portion of the adjacent shingle. This shingle nail secures the adjacent shingles to each other and also permanently secures the shingles to the roof. 70 The device is also provided with a plurality of tabs adapted to accurately position and space adjacent shingles to prevent wind from blowing through the spaces between the shingles and to secure the butts of the 75 shingles, thereby preventing them from being blown up by the wind. Further details of the invention will appear from the following description.

In the particular form of the invention 80 illustrated, each shingle 10 has secured thereto along one edge 11, a spacing and securing device 12. This device is preferably formed of relatively thin sheet metal such as sheet copper and may be secured to the 85 shingle in any desired manner. In the form of the invention shown, the device 12 has portions 13 and 14 punched out and pressed through the shingle, the ends 15 of the punched out portions being bent around as 90 shown in Fig. 2 to firmly and permanently secure the device to the shingle.

Each of the devices 12 has a portion 16 which extends beyond the edge of the shingle 11 to which it is secured and is adapted to 95 overlap an edge of the adjacent shingle. Each device 12 also has formed thereon a plurality of tabs 17, 18 and 19 for purposes hereinafter described.

One method of using the shingles is illustrated in Fig. 3 which shows portions of five shingles, A, B, C, D and E. Each of these shingles has one of the devices 12 secured to the left hand edge thereof. It will be noted that the tab 19^c carried by 100 the device 12^c secured to the shingle C is bent inwardly or toward the roof as shown in Fig. 4 and forms a barrier or stop for 105

preventing wind from blowing through the space between the shingles B and C. Furthermore, the tab 18^c carried by the device 12^c is bent outwardly and upwardly over the lower edge or butt of the shingle A, thus preventing the butt from being blown up by the wind. The portion 16^c has a nail 25 extending therethrough and through the adjacent edge of the shingle B. This nail 10 secures the shingles B and C together and also secures the shingles to the roof.

The tabs 19^c and 18^c provide means for accurately spacing the shingles B and C.

The tabs carried by the other shingles, 15 A, B, D and E, coact in a similar manner with adjoining or adjacent shingles. It will be noted that when the shingles are laid in the manner shown in Fig. 3 the tabs 17 do not perform any function.

20 Another method or manner of laying shingles is illustrated in Fig. 8 wherein there are shown portions of seven shingles, A, B, C, D, E, F and G.

From the showing in Figs. 8 and 9 it 25 will be noted that the tab 17^a of the device 12^a secured to the shingle A is bent outwardly and forms a spacer for shingles D and E and is bent around the butt of the shingle F, thus securing the butt of this 30 shingle and the adjacent shingles D and E from being blown up or raising from the roof. When the shingles are laid in the manner shown in Figs. 8 and 9, the tabs 18 and 19 perform no useful function.

35 Fig. 10 illustrates a practical method of piling the shingles for shipment. It will be noted that alternate shingles are reversed so that the projecting portions 16 of the devices 12 are superimposed on the opposite 40 edges of the adjacent shingles. When the shingles are stacked in this manner the projecting portion 16 of the device 12 will not extend beyond the edges of the shingles disposed adjacent thereto.

45 From the foregoing description it will be seen that simple and practical means has been provided for facilitating the laying and securing of shingles and, furthermore, that the device constructed as described will 50 effectively prevent shingles from blowing up

from a roof and will also prevent the circulation of air through the spaces between adjacent shingles.

Although one specific embodiment of the invention has been particularly shown and described, it will be understood that the invention is capable of further modification and that changes in the construction and in the arrangement of the various cooperating parts may be made without departing from the spirit or scope of the invention, as expressed in the following claims.

What I claim is:

1. A shingle having a metallic plate secured thereto adjacent an edge thereof and extending beyond said edge, said plate having a tab projecting therefrom in a direction opposite said extension adapted for use when the shingle is laid in one position and having oppositely projecting tabs on the extension thereof, adapted for use when the shingle is laid substantially at right angles to said position.

2. A shingle having a metallic plate secured thereto adjacent an edge thereof and extending beyond said edge, said plate having a tab projecting therefrom in a direction opposite said extension adapted for use when the shingle is laid in one position and having oppositely projecting bendable tabs on the extension thereof, adapted for use when the shingle is laid substantially at right angles to said position.

3. A shingle securing and spacing means comprising a centrally disposed body portion, having an extension along one side thereof, and a tab projecting therefrom in a direction opposite said extension, said extension having oppositely projecting tabs disposed substantially at right angles to said first tab, said body adapted for attachment to a shingle, said first named tab adapted for use when laying shingles in one course, and said last named tabs adapted for use when laying shingles substantially at right angles to said first named course.

In witness whereof, I have hereunto set my hand this 1st day of November, 1926.

WILLIAM A. SCHOLLMAYER.
